DESIGN FOR AN AUTOMOBILE STEERING WHEEL COVER

Frank P. Jackson, Chicago, Ill.

Application August 29, 1934, Serial No. 53,108

Term of patent 14 years

To all whom it may concern:

Be it known that I, Frank P. Jackson, a citizen of the United States, residing at Chicago, in the county of Cook, State of Illinois, have invented a new, original, and ornamental Design for Automobile Steering Wheel Cover, of which the following is a specification, reference being had to the accompanying drawing, forming a part thereof.

Fig. 1 is a top plan view showing the automobile steering wheel cover of my design;

Fig. 2 is an edge view thereof; and
Figs. 3 and 4 are sectional views taken on the
lines 3—3 and 4—4, respectively, shown to a
somewhat enlarged scale.

I claim:

The ornamental design for an automobile steering wheel cover as shown.

FRANK P. JACKSON.
